Attns.

UNITED STATES PATENT OFFICE.

HOWARD D. TAYLOR, OF NEW YORK, N. Y.

CAR-TRUCK BOLSTER.

Application filed February 5, 1925. Serial No. 6,915.

The invention relates to bolsters for railway car trucks and seeks to provide a bolster of strong construction and which is adapted for use with the improved car truck set forth in an application for Letters Patent filed in the United States Patent Office May 16, 1924, Serial No. 713,675. The invention consists in the features of improvement hereinafter set forth, illustrated in the preferred form in the accompanying drawing and more particularly pointed out in the appended claims.

In the drawings:

Fig. 1 is a side elevation of the truck with the improved bolster applied thereto and shown in end elevation.

Fig. 2 is a view of the bolster partly in plan and partly in horizontal section on the line 2—2 of Fig. 3.

Fig. 3 is a view of the same partly in side elevation and partly in vertical section on the line 3—3 of Fig. 2.

As set forth in the application for Letters Patent above noted and as illustrated in Fig. 1, the car truck side frames *a* are provided with enlarged central portions having circular bearing openings of considerable size within which carrier rings *b* are journaled. The rings are interlocked with the side frames by means of keys 10 to permit the limited rocking movement of the side frames in vertical planes and a truck bolster *c* and spring plank *d* interlock with the carrier rings to connect the opposite sides of the truck. For this purpose, each carrier ring is provided with a bolster opening having columns 11 at opposite sides thereof and a supporting sill 12 at its lower end. The end of the spring plank *d* rests on the sill 12 and interlocks therewith as by means of a depending stud 13 on the plank engaging a socket in the sill. The upper portions of the columns are provided with inwardly projecting lugs or guides 14 which co-operate in the usual manner with column guides or lugs 15 on the ends of the bolster and the upper ends of the lugs 14 merge into the arch-shaped portion 16 of the ring at the upper end of the bolster opening. A set of springs *e* is interposed between the ends of the spring plank and bolster, and if desired, the set of springs can be connected together by suitable cap plates. In assembling the parts, the end of the bolster is first inserted in the lower portion of the bolster opening and is then raised to interlock the column

guide lugs 14 and 15. Then, by inserting the spring plank and the set of springs, the bolster and spring plank will be maintained in interlocked relation with the side frame. 60

The improved truck bolster comprises an upper compression member 17, a lower tension member 18, and intermediate stiffening side members 19 arranged in vertical planes. In the form shown, these members 65 constitute respectively the top, bottom, and side walls of an integral hollow casting. But, if desired, these parts may be formed of two or more pressed steel sections. To permit sufficient play in the bolster openings of the carrier rings and ample space for the springs without unduly increasing the size of these openings and of the rings, the upper walls of these openings are arched as described and the end portions of the top 70 wall or compression member 17 of the bolster are correspondingly arched in cross-section. Also, for this purpose, the end portions of the bolster which engage the springs are considerably reduced in height and the 75 tension member or bottom wall 18 has portions, inclined upwardly from the central portion of the bolster, that merge into and terminate in substantially horizontal spring-engaging portions or seats 20. To provide 80 a bolster of proper strength notwithstanding the reduction in height at its ends, the top wall or compression member 17 is arched in section from the ends of the bolster nearly to the central bearing portion 21 thereof, 85 and the convexity of this arch gradually increases from the central portion of the bolster to its ends. That is to say, adjacent the central bearing portion 21 the top wall is substantially flat and each end portion arranged 90 within the carrier ring *b* conforms substantially to the curvature of the arched portion 16 at the upper end of the bolster opening. But between these points there is no break or offset in the cross-section of the top 95 wall or compression member of the bolster. It is however provided adjacent its ends, in the form shown, with thickened portions 22 having flat upper surfaces for supporting suitable side bearings. Also, to strengthen 100 and stiffen the bolster, the side walls 19 are extended below the spring seats 20 and the inclined portions of the lower tension member or bottom wall 18, to form stiffening flanges 23 that are preferably connected at 105 points adjacent the inner ends of the spring seats by transverse flanges 24. Vertically 110

disposed stiffening parts or ribs 25 are also interposed between the spring seats 20 and the arched end portions of the top wall of the bolster. The central portion of the bolster may be made of any suitable or usual construction. In the form shown, the central portions of the upper and lower members or walls are connected by vertical portions 26 that are strengthened by bracing ribs 27.

10 Changes may be made in the details set forth without departure from the scope of the invention as defined in the claims.

I claim as my invention:

1. A car-truck bolster having top, bottom and side walls, the ends of the top wall being arched and the end portions of the bottom wall forming spring seats above the lower edges of said side walls, and the bolster having stiffening parts between said arched ends and said spring seats, substantially as described.

2. A car-truck bolster having an enlarged central portion and contracted end portions, and comprising top, bottom and side walls, the ends of the top wall being arched and the ends of the bottom wall forming spring seats, and the bolster having stiffening ribs or flanges above and below the spring seats, substantially as described.

3. A car-truck bolster having contracted ends and comprising a top wall having arched end portions, a bottom wall inclined upwardly from the center of the bolster and terminating in spring seats, side walls depending below said spring seats and the inclined portion of the bottom walls, and stiffening parts between said spring seats and the arched ends of said top wall, substantially as described.

4. A cast, hollow, car-truck bolster having contracted end portions provided with column guides, and comprising a top wall having arched ends, side walls, and a bottom wall inclined upwardly from the center of the bolster and terminating in spring seats, and the bolster having stiffening ribs between said seats and the arched ends of the top wall and depending stiffening flanges at the side edges of the seats and of the inclined portions of the bottom wall, substantially as described.

5. A car truck bolster comprising a top

wall having a flattened central portion merging gradually into an arched section that gradually increases in convexity from the center to the bolster ends, and substantially continuous stiffening side walls depending from the edges of the top wall, substantially as described.

6. A car-truck bolster comprising a top wall having a flattened central portion merging gradually into arched end portions that increase in convexity from the central portion thereof to its ends, depending side walls, and a bottom wall having portions upwardly inclined from the central portion of the bolster and terminating in horizontal spring seats, substantially as described.

7. A car-truck bolster comprising an upper compression member having arched end portions, stiffening side members, and a lower tension member having portions inclined upwardly from the central portion of the bolster and terminating in spring seats disposed above the lower edges of said side members, substantially as described.

8. A car-truck bolster having contracted end portions and comprising an upper compression member having arched ends, a lower tension member terminating in spring seats, and vertically disposed stiffening members between said compression and tension members and depending below said seats, substantially as described.

9. A car-truck bolster comprising a top wall having an arched section that is flattened adjacent the central portion of the bolster, gradually increases in convexity from the center to the bolster ends and is provided with thickened portions adjacent its ends forming side bearing seats and stiffening ribs or flanges depending from said top wall, substantially as described.

10. A car-truck bolster having an enlarged central portion and contracted ends and comprising an upper compression member having arched ends, a lower tension member terminating in flat, horizontal spring seats, vertical side members and additional vertically disposed stiffening members between the central and end portions of said compression and tension members.

HOWARD D. TAYLOR.
